United States Patent

Des. 235,914
Patented July 15, 1975

235,914

LIGHTING FIXTURE

Arthur Schacht, East Hills, N.Y., assignor to
Crystal Mart, Inc., Deer Park, N.Y.

Filed Oct. 30, 1974 Ser. No. 519,280

Term of patent 14 years

Int. Cl. D26—05

U.S. Cl. D48—3

FIG. 1

FIG. 2

FIG. 7

FIG. 3

FIG. 4

FIG. 5

FIG. 6

FIG. 1 is a perspective view of a lighting fixture showing my new design;

FIG. 2 is a top plan view thereof;

FIG. 3 is a front elevation view thereof;

FIG. 4 is a right side elevation view thereof;

FIG. 5 is a rear side elevation view thereof;

FIG. 6 is a left side elevation view thereof; and

FIG. 7 is a sectional view thereof along lines 7-7 of

FIG. 3.

The chain and lamp sockets are shown in broken lines in FIGS. 1, 2 and 3 for illustrative purposes only.

I claim:

The ornamental design for a lighting fixture, substantially as shown and described.
